United States Patent Office

Des. 179,195
Patented Nov. 13, 1956

179,195

TOTE BOX

Roger E. French and Nicholas W. Keller, New Kensington, Pa., assignors to Aluminum Company of America, Pittsburgh, Pa., a corporation of Pennsylvania

Application March 22, 1955, Serial No. 35,156

Term of patent 14 years

(Cl. D58—12)

Fig. 1.

Fig. 2.

Fig. 3.

Fig. 1 is a top plan view of a tote box embodying our new design;

Fig. 2 is a view of the same in side elevation; and

Fig. 3 is a view in end elevation.

We claim:

The ornamental design for a tote box, substantially as shown.
